DESIGN FOR A SMOKING STAND

Louis Meyer, Brooklyn, N. Y., assignor to J. Bennett Inc., Brooklyn, N. Y., a corporation of New York

Application March 16, 1939, Serial No. 83,603

Term of patent 7 years

To all whom it may concern:

Be it known that I, Louis Meyer, a citizen of the United States, a resident of the Borough of Brooklyn, county of Kings, city and State of New York, have invented a new, original, and ornamental design for a Smoking Stand, of which the following is a specification, reference being had to the accompanying drawing forming a part thereof.

Fig. 1 is a side elevational view of the smoking stand showing my new design.

Fig. 2 is a top plan view.

I claim:

The ornamental design for a smoking stand, substantially as shown.

LOUIS MEYER.
